UNITED STATES PATENT OFFICE.

BRUCE FORD, OF PHILADELPHIA, PENNSYLVANIA.

STORAGE BATTERY.

1,182,998.

Specification of Letters Patent.

Patented May 16, 1916.

Application filed March 2, 1914. Serial No. 821,887.

To all whom it may concern:

Be it known that I, BRUCE FORD, a citizen of the United States, residing at Philadelphia, in the county of Philadelphia and State of Pennsylvania, have invented certain new and useful Improvements in Storage Batteries, of which the following is a specification.

The principal object of the present invention is to provide a combined stopper and vent which will minimize or prevent the egress of liquid from the battery jar either by splashing or by being carried as spray with the gas or gases that are permitted to escape freely from the interior of the jar through the stopper.

The invention will be claimed at the end hereof but will be first described in connection with the embodiments of it chosen for illustration in the accompanying drawings in which—

Figure 1, is a side view, principally in section, of so much of a storage battery jar and its stopper as is necessary for a description of the invention. Fig. 2, is a similar view of a portion of the stopper or vent showing the same to embody a modification of the invention, and Fig. 3, is a view similar to Fig. 1, illustrating another modification.

Referring to Fig. 1, the stopper body 1, has a hollow interior constituting an expansion chamber 2, and the top of the stopper body 1, is provided with a concavity 3. The expansion chamber is in communication with the concavity by an opening or port 4, and the expansion chamber is in communication with the interior of the jar by openings or ports 5 and 6. As shown in Fig. 2, the construction is the same as that illustrated in Fig. 1, except that the stopper body is closed at the bottom and the ports 7 are arranged horizontally. The construction and arrangement shown in Fig. 3, is substantially the same as in the other figures except that several ports 4^a and 4^b, are employed for connecting the expansion chamber with the concavity and except that the ports 5^a and 6^b, are arranged horizontally.

7, is a portion of the jar cover in which the stopper as a whole is detachably fitted.

In use gas entering the expansion chamber 2, carries with it liquid in the form of vapor, spray or mist, and this liquid by reason of the restriction in velocity of the vapor condenses or is deposited in the expansion chamber so that it does not pass to the concavity 3, along with the gas; any liquid that does reach the concavity flows back into the expansion chamber and thence to the interior of the jar. So far as splashing is concerned the walls of the expansion chamber acting as baffles prevent the escape of liquid from the interior of the jar, even if some liquid should splash into the expansion chamber.

What I claim is:

1. A stopper for battery jars consisting of a body having a hollow interior constituting an enlarged expansion chamber and having in its top a concavity and provided with ports connecting the concavity and expansion chamber and with other ports at different levels extending from the expansion chamber through the wall of the stopper and adapted to communicate with the interior of a jar and of which some pass gas while others pass returning liquid, whereby the venting operation is uninterrupted.

2. A stopper for battery jars comprising a stopper body having a hollow unobstructed interior constituting an enlarged expansion chamber and having a concavity in its top and an imperforate bottom and provided with ports from the expansion chamber to the concavity and with other ports at different levels leading from the expansion chamber through the stopper wall above the imperforate bottom and whereof some pass gas and others simultaneously pass liquid, whereby the venting operation is uninterrupted, substantially as described.

BRUCE FORD.
